BIPOLAR MAGNETIC CONTROL RECORDED

Robert I. Roth, Hawthorne, N. Y., assignor to
International Business Machines Corporation,
New York, N. Y., a corporation of New York

Application January 31, 1945, Serial No. 575,511

7 Claims. (CL 235—61,12)

1

This invention relates to control records for record controlled machines and particularly to records of the magnetic spot type.

One object of the invention is to provide a record of this type having stronger magnetic spots, that is, spots which will produce a stronger signal in a magnetic spot sensing device.

Another object is to provide a control record having magnetic spots capable of producing distinctly different responses in a sensing device, depending upon novel differentiating characteristics of the spot.

Another object is to increase the capacity of a record area.

Another object is to increase the secrecy of a record.

Another object is to provide a control record whereon positive and negative amounts are distinguished by the nature of the individual spots which represent the amounts by their positions on the record.

Another object is to provide a control record whereon data are represented by significantly located magnetic spots having further distinguishing characteristics indicating the class of the data.

Another object is to provide a control record having magnetic spots representing data in accordance with a code wherein the variables include, in addition to the positions of the spots, certain differentiating characteristics of the individual spots.

In accordance with the principle of the invention the above mentioned objects are realized by providing the record with bipolar magnetic spots, with their axes in the plane of the record sheet, as will be described in detail presently.

Other objects of the invention will be pointed out in the following description and claims and illustrated in the accompanying drawings, which disclose, by way of example, the principle of the invention and the best mode, which has been contemplated of applying the principle.

Fig. 1 is a diagram of apparatus for making a record in accordance with the principle of the invention.

Fig. 2 is a diagram illustrating the principle of licensing a record made in accordance with the invention.

Fig. 3 is a diagram of the voltage induced in sensing coil on sensing spots of opposite polarity.

Figs. 4 and 5 are respectively a tape and a

card formed of magnetic spot record embodying the invention.

Fig. 1 shows a soft iron backing plate 10, at one side of which is positioned a record sheet 11 composed of, partially composed of, or coated with, paramagnetic material. Preferably, the record sheet is a special paper into which a magnetizable material in finely divided state is incorporated when the paper is made. The magnetizable material should have a high coercive force. An alloy of aluminum, cobalt, nickel and iron having the composition 12% Al, 20-28% Ni, 5% Co, balance Fe, known commercially as Alnico, makes a particularly good magnetic spot record. Before being treated to produce magnetic spots, the sheet is rendered uniformly non-magnetized by any suitable means.

On the opposite side of the sheet 11 from the backing plate 10 is a two-pole electromagnet 12 having windings 13 on its core 14 such that, when current is passed through them, the poles 15 and 16 will be oppositely magnetized. The windings 13 of the magnet are connected to two blades 17, 18 of a reversing switch 19 having cross-connected contacts 20, 21, and 22, 23. The contacts 22 and 23 are connected to one side, +, of a source of direct current (not shown), and also to one plate of a condenser 24. The contacts 20 and 21 are connected to a normally open terminal 25 of a switch 26, the movable blade 27 of which is connected to the opposite side of the condenser 24 and normally rests against a contact 28 connected to the other side —, of the source of direct current. By throwing the switch blade 27 against the contact 25, when the reversing switch is in the position shown in Fig. 1, the charge on the condenser 24 flows through the coils of the electromagnet in the direction to render the right hand pole 16 a north pole and the left hand pole 15 a south pole. This produces a bipolar magnetic spot on the record having a south pole at its right end and a north pole at its left end. The purpose of the backing plate 10 is to concentrate the flux and thus produce a sharply defined spot.

After making a spot, in the manner described, the sheet 11 can be moved, by any suitable means, to bring a different area over the poles of the recording magnet. Also, the switch blade 21 is returned to contact 28, to recharge the condenser 24. Then if the blades 17, 18 of the reversing switch 19 are thrown to the opposite contacts 21, 22 and the blade 21 is moved against the contact 25, the discharging current of the condenser will pass through the coils of the electromagnet in the

opposite direction, producing a magnetic spot of opposite polarization, that is, with a north pole at the right end and a south pole at the left end.

Fig. 2 illustrates the procedure in sensing magnetic spots of the kind produced in the manner illustrated in Fig. 1. The record 11 is fed, by any suitable means (not shown), across one end of the core 30 of an electromagnetic sensing device 31, hereinafter called a sensing magnet, in the direction indicated by the arrow 32. The sensing magnet 31 has a coil 33 which can be connected to a storage device (not shown), or any means which is to be responsive to the magnetic spots. The record is shown with two highly magnified bipolar magnetic spots 34 and 35, the north poles 36, 36' of which point in opposite directions. It will be noticed that each magnetic spot is like a small bar magnet, the axis of which lies in the plane of the record sheet and parallel to a common reference line, which, in this case, is the direction of feed of the record sheet.

I have observed that, when spots of the kind shown in Fig. 2 are sensed by a sensing magnet, voltages are induced in the coil of the sensing magnet as shown in Fig. 3. Each spot induces a voltage following a curve which begins with a small loop 37, 37' in one direction, then makes a sharp peak 38, 38' of much greater magnitude in the opposite direction, and finally passes through a small loop 39, 39' in the first direction. The two spots induce opposite voltages, due to the different orientation of their north poles. Thus, if the peak 38 of the voltage induced by the first spot is regarded as positive, the peak 38' induced by the second spot is negative. The reason for the peculiar voltage curves is as follows: The voltage induced in the coil 33 of the sensing magnet is directly proportional to the rate of change of flux in the core 30. As the record moves over the sensing magnet, the south pole 40 of the first spot sets up a flux in the core 30, which increases in density until the center of the core reaches the center of flux density 41 emanating from the south pole of the spot. At this time the flux density in the core 30 reaches a constant, maximum value, hence there is no change of flux to induce a voltage in the coil of the sensing magnet. Up to the time when the center of the core reaches the spot 41, the voltage in the coil 33 traces the curve 37, reaching a maximum in the negative direction and returning to zero, being at all times directly proportional to the rate of change of flux density in the core. When the center of the core passes the spot 41, the flux in the core decays, and a positive voltage is induced in the coil of the sensing magnet, indicated by the peaked curve 38. As the core of the sensing coil begins to enter the flux emanating from the north pole, flux of opposite direction is set up in the core, which hastens the rate of decay of the total flux in the core.

When the center of the core reaches a point midway between the south and north poles of the spot, the flux in the core is changing at a maximum rate, hence the voltage induced in the coil of the sensing magnet is at its positive peak. From that point on, the flux becomes more and more predominantly controlled by the north pole of the spot and the voltage induced in the coil continues to be positive, but the rate of change of the flux decreases, until the center of the core reaches the spot 43, indicating the point of greatest density of the flux emanating from the north pole of the spot. At this time the rate of change of the flux in the core of the sensing mag-

net becomes zero, the density of the flux in the core having reached a maximum. The voltage induced in the coil is therefore zero. As the spot continues across the core, the flux in the core decays, reaching a maximum rate of decay when the center of the core passes some point between the point 43 and the boundary of the magnetic spot. The voltage induced in the coil 33 during this time traces the curve 39.

When the second spot crosses a core of the sensing magnet, the voltage traces a curve exactly the reverse of the one just described.

I believe the height of the peak voltage, as compared to the relatively small beginning and ending curves, is due to several influences. First is the simultaneous influence of the diminishing flux set up by the south pole and the increasing flux set up by the north pole, the latter increasing the rate of decay of the flux set up by the south pole. Also, the centers of density of the flux emanating from the south and north poles are shifted toward each other by their mutual influence, thus causing the rate of change of flux density in the core to be greater as the core moves between the points 41 and 43 of maximum flux density in the two poles of the spot, than when the core is moved through the more dispersed flux outside of the two centers of density. Whatever the reason, the voltage induced by a bipolar spot is considerably greater than that induced by a monopolar spot. In addition to this, the voltage induced by the bipolar spot is asymmetric, which affords the possibility of giving two distinct meanings to a spot, according to its orientation. The latter feature is of considerable importance in control records, because it means that a given amount of information can be represented on a smaller area. Thus, in a telegraphic tape it is possible to represent all the digits and the entire alphabet, as well as additional characters, by means of a 4-position bipolar magnetic spot code, wherein the orientation of the north pole of the spot is one of the variables. A small sample of a telegraphic tape of this type is shown in Fig. 4. In this figure the spots are represented by arrows and their orientation is indicated by the direction in which the arrows point. A telegraphic tape of this kind also has a higher degree of secrecy than one with monopolar spots, because the bipolar characteristic, which constitutes one of the variables of the code, would not be readily detected.

Another advantage of the bipolar magnetic spot record is illustrated by the statistical card partially shown in Fig. 5. In this case the spots are again represented by small arrows. Those in field 50 represent the positive value 364, the positive nature of this value being represented by the orientation of the bipolar magnetic spots. In field 51 the spots have the reverse orientation, indicating that the number 27, which they represent, is a negative number. Field 52 contains spots representing the difference of the numbers in fields 50 and 51, namely 337. Since this is a positive value, the magnetic spots have the same orientation as those in field 50.

Positive and negative values are mentioned as illustrative of different classes of data which can be identified by oppositely orientated bipolar magnetic spots. The different orientations can be used to represent any other classification.

While there have been shown and described and pointed out the fundamental novel features of the invention as applied to a preferred embodiment, it will be understood that various

omissions and substitutions and changes in the form and details of the device illustrated and in its operation may be made by those skilled in the art, without departing from the spirit of the invention. It is the intention, therefore, to be limited only as indicated by the scope of the followings claims.

What is claimed is:

1. In a control record for a record controlled machine having a monopolar reading device, the record being read by relative motion of the record and the reading device, a sheet of generally non-magnetized material having significantly located discrete bipolar magnetic spots, the axes of the spots being in the plane of the sheet and parallel to the direction of relative motion of the record and the reading device.

2. In a control record for record controlled machines having monopolar means to read the control record in motion, a sheet of generally non-magnetized material having significantly located discrete bipolar magnetic spots, the axes of the spots being in the plane of the sheet and parallel to the direction of feed of the sheet.

3. In a control record for record controlled machines having monopolar means to read the control record in motion, a sheet of generally non-magnetized material having significantly located discrete bipolar magnetic spots, the axes of the spots being in the plane of the sheet and parallel to the direction of feed of the sheet, and with either the north or south pole leading, depending upon the data signified.

4. In a control record for a record controlled machine having a monopolar reading device, the record being read by relative motion of the record and the reading device, a sheet composed at least partly of generally unmagnetized paramagnetic material having significantly located discrete bipolar magnetic spots disposed with their axes in the plane of the sheet and their north poles directed in either of two opposite directions parallel to the direction of the relative motion of the record and the reading device.

5. A record tape for reading by a monopolar tape reader, said record tape having discrete bipolar magnetic spots arranged thereon with their axes in the plane of the tape and parallel to its direction of feed, the spots being disposed

in different code positions of the tape and with their north poles either leading or trailing, in accordance with a combinational code wherein the direction of the north pole of the spot is one of the variables.

6. In a control record for record controlled statistical machines having monopolar record reading means, the record being read by relative motion of the record and the reading means, 10 a sheet composed at least partly of generally unmagnetized paramagnetic material having discrete bipolar magnetic spots located thereon in accordance with a statistical code, the axes of the magnetic spots being in the plane of the sheet with the north poles of the spots pointing in either of two opposite directions parallel to the direction of relative motion of the record and the reading means, depending upon the class of data represented by the spot.
- 20 7. In a control record for record controlled statistical machines having monopolar record reading means, the record being read by relative motion of the record and the reading means, a sheet composed at least partly of generally unmagnetized paramagnetic material having discrete bipolar magnetic spots disposed with their axes in the plane of the sheet and located in selected index point positions of different columns of the sheet parallel to the direction of relative motion of the record and the reading means, 30 the columns being grouped in different fields and the spots in a certain field being oriented with their north poles pointed parallel to the columns in one direction, while the spots in another field are oriented with their north poles pointing in the opposite direction.
